METHOD OF TREATING HYDROCARBON
MOTOR FUELS AND PRODUCTS RESULT-
ING THEREFROMGeorge W. Ayers, Jr., Chicago, Ill., assignor, by
mesne assignments, to Gasoline Antioxidant
Company, Wilmington, Del., a corporation of
DelawareNo Drawing. Application October 1, 1934,
Serial No. 746,419

4 Claims. (Cl. 44-9)

This invention relates to the treatment of hydrocarbon oils, particularly to those oils suitable for use as motor fuels. With reference to its more specific aspects, the invention has to do with the treatment of cracked distillates, particularly those distillates produced by high temperature or vapor phase cracking methods, to prevent or minimize the formation of gums or gum compounds in distillates of this character.

Cracked petroleum products, particularly gasoline, upon being exposed for some time to air, light or heat, form resinous materials which may be dissolved by the petroleum product or which may form an insoluble deposit. These resinous products are formed particularly in large amounts when vapor phase gasoline, that is, gasoline which contains a large per cent of unsaturated compounds is stored for several months. If a tank car of gasoline, for example, is exposed for some time to the heat of the sun, formation of these undesirable resinous products is accelerated. If these gums are permitted to form and remain in the motor fuel product they are apt to interfere with the proper flow of the motor fuel through the fuel passages of internal combustion engines by permitting the gum to deposit in such passages to an extent sufficient to clog or obstruct the passages against the free and proper flow of the fuel to the combustion cylinders.

It is, therefore, an outstanding object of the invention to treat motor fuels containing large quantities of unsaturated constituents with compounds which for convenience may be termed negative catalysts or inhibitors, which we have discovered will arrest for all practical purposes the formation of the objectionable resinous or gum compounds in the motor fuel product, so that the latter may be subjected to the conditions prevailing in the storage, transportation and handling of motor fuel products without any appreciable developments of the gum substances in said fuel.

We have found that certain substances when added to petroleum products slow down the rate of formation of these resinous products. For example, when catechol is added to motor fuel oil containing unsaturated compounds, the gum formation is inhibited almost entirely for several months. A large number of amino and hydroxy compounds of the aromatic series were added to gasoline and it was found that practically all of them had some inhibiting effect upon gum formation. We are of the opinion that this inhibition of gum formation is characteristic of these two classes of compounds, although there is a difference in effect, depending upon the particular compound employed. Other compounds also were found to exert this inhibitive effect. For example, the effect of some of these

inhibiting agents may be seen in the following table, which represents the action of the factors which contribute to the formation of gum in vapor phase cracked gasoline, namely, light, oxygen and heat:

Table 1

Inhibitive agent (original gum)	Gum after 8 days	Gum after 24 days	Gum after 35 days	10
Blank.....	.0026	*.0259	.0399	.0447
Catechol.....	.0020	.0043	.0064	
Pyrogallic acid.....	.0021	.0062		
Aniline.....	.0071	.0124	.0131	
Nitrobenzene.....	.0134		.0245	
Phenol.....	*.0176	.0218		15

* Gum after 7 days.

The values shown above represent the amount of gum formed on evaporating 20 c. c. of the gasoline in a glass dish of approximately 30 c. c. capacity and of approximately 10 grams weight, by placing said materials in a steam bath for three hours, and then drying for 30 minutes in a heated oven maintained at 105° C.

We have determined, furthermore, that when cracked petroleum products, notably gasolines, are oxidized by heat, the velocity or rate of oxidation increases with the time; that is to say, the reaction is auto-catalytic. This is apparently due to the catalytic effect of the oxidized bodies. In order to combat this auto-catalysis we have used ammonia and organic substitution compounds thereof, in other words, compounds which might combine with the aldehydes, ketones or acids formed by oxidation. When heated in glass dishes on the steam or water bath, according to the method previously explained, not only was the gum formation inhibited, but apparently the nature of the residue seemed altered, being mainly a light-colored oily liquid rather than a deep orange-colored gummy residue. Characteristic results are given below, using untreated, vapor phase cracked gasoline as the medium:

Table 2

Added agent	Gum	45
Gasoline.....	.1639	
Gasoline and ammonia.....	.1373	
Gasoline and diphenylguanidine.....	.1466	50

In any case the inhibiting materials may be either in solution or suspension in the gasoline. Gasoline or motor fuel oil containing gum producing compounds is produced by the passing of petroleum vapors through a heated reaction zone wherein the vapors for a desired period of time are brought to a temperature usually in excess of 1000° F., in which reaction zone the de- 55
60

sired pyrogenetic decomposition of the hydrocarbon compounds takes place with the result that a relatively large quantity of lower boiling hydrocarbons are obtained from the original higher boiling hydrocarbons comprising the stock under treatment. These low boiling hydrocarbons are suitable for use as motor fuel, and upon emerging from the conversional reaction zone the vapors are subjected to fractional condensation to separate the desired low boiling compounds from the higher boiling compounds. The low boiling vapors are then passed through a polymerizing catalyst, such as fuller's earth for the purpose of removing therefrom a very large 15 percent of the undesirable unsaturated compounds which produce the gummy or resinous substances and which also tend to discolor the oil. In spite of these precautions, however, it has been found that the gum compounds accumulate or form in treated motor fuel products, and we therefore employ the inhibiting compounds of the character above set forth to minimize or prevent the formation of gums in the finished or treated fuel. It is, of course, possible 20 to apply these inhibiting compounds to untreated fuels, that is, to the fuels which are obtained directly, without condensation, from the conversion zone of the cracking apparatus. This would require the use of a greater amount of the anti-gum forming compounds than in the case of controlling the treatment of cracked gasolines which had been contacted in the vapor phase with fuller's earth. Amounts as low as 0.001 to 0.004% 25 may be used satisfactorily.

30 The apparent effect of various substances on the rate of gum formation in the light and in oxygen has been observed. For example, a sample of refined vapor phase gasoline was used with about .002 g. of gum per 20 c. c.; four oz. 35

40 sample bottles were filled with the gasoline and small amounts of the anti-gum forming agents were added, after which oxygen was placed in the air space at the top of the bottle and tests were made over periods of 7, 8, 24 and 35 days.

45 to determine the rate and quantity of gum formation or inhibition.

The hydroxy-compounds of benzene have been found to possess qualities which render them adaptable as negative catalysts or inhibitors, 50 the best inhibiting effect being obtained with the compounds having the greatest number of hydroxy groups. In the case of pyrogallic acid the gum remained practically constant for 35 days, as was also the case with catechol. Hydroquinone allowed a small amount of gum to form in addition to that already present in the gasoline as did resorcinol. Phenol when used disclosed quite satisfactory inhibiting effects.

On the other hand, the alcohols were substantially without effect in attaining the ends of the invention, except in the case of methyl alcohol, which was found to possess a very mild negative catalytic action. Ethyl alcohol, butyl alcohol and iso-amyl alcohol had practically no effect 65 whatsoever.

Next to the hydroxy-compounds of the benzene series, the amino-compounds were considered to be the best inhibitors of gum formation. Aniline served as an extremely good negative 70 catalyst, with diphenylamine next in order. The substituted anilines—dimethyl-aniline and diethyl-aniline—had the same effect and are considered to be good anti-catalysts. Hexamethylene-tetramine showed a negative catalytic effect, 75 but drops of gum were deposited on the bottom

of the test bottle. In this regard the following were found to be accelerators of gum formation in the order of their effect: Aluminum oleate, carbon tetrachloride, calcium chloride, manganese borate, tannic acid, pepsin, benzaldehyde and benzoyl peroxide. Nitrobenzene is considered a fair anti-catalyst, as is also acetone. 5

The following tables disclose results of gum tests on vapor phase gasoline to which the various anti-gum compounds have been added. 10

* Strong varnish odor in sample bottle after remaining in contact with Cu.

In view of the foregoing it will be seen that the present invention provides a method of treating cracked petroleum distillates having large quantities of highly reactive or unsaturated compounds therein with other compounds having the properties of inhibitors or anti-catalysts by which the further formation of gum compounds in the cracked distillate is substantially prevented or minimized. This method of treating has the desirable effect of permitting treated or untreated vapor phase distillates to be handled in a manner customary to the storage and shipment of motor fuels without further development of the highly objectionable and undesirable gums and resinous compounds. The anti-catalytic substances do not impair in any way the value of the cracked distillate so treated in any respect since the amount of the anti-catalysts employed in accomplishing the purpose of the invention is relatively small and further, the anti-gum forming materials themselves are of such character as to be readily consumed in the cylinders of the internal combustion engine. 55

The proportions of the oxidation inhibitors which may be added to cracked petroleum distillates to prevent gum formation varies, of course, with the particular inhibiting compound selected 60

75

and also with the percentage of gum forming compounds originally present in the treated distillates. It is advisable to conduct tests in the handling of each inhibitor and its application to any particular distillate to obtain the data necessary in each particular case. Usually, however, the amount of the inhibitor will constitute but a fraction of one per cent. of the total volume of the distillate so treated. The concentration 10 may vary from 0.001 to 0.006% and with some inhibitors concentrations up to 0.009% may be used. Expressed in other terms, the inhibitor may be added in proportions of ten pounds per one thousand barrels to the cracked distillate to prevent gum formation during ordinary handling, storage and transportation of the fuel.

15 This application is a continuation in part of my copending application Serial No. 309,685, filed October 1, 1928.

I claim:

1. The process of producing stabilized gasoline from distillate resulting from vapor phase cracking of hydrocarbon oil which comprises contacting said distillate with an adsorptive polymerizing catalyst at a temperature at which a substantial portion of the distillate is in the vapor phase and thereafter adding to said distillate a small proportion of an amino benzene in sufficient amount to inhibit formation of gum. 5
2. A process in accordance with claim 1 in which the inhibitor is aniline. 10
3. A process in accordance with claim 1 in which the inhibitor is dimethyl aniline. 15
4. A process in accordance with claim 1 in which the inhibitor is diethyl aniline.
